UNITED STATES PATENT OFFICE

HERMANN H. ZORNIG, OF THE UNITED STATES ARMY, NEWHALL, IOWA

FUSE FOR PROJECTILES

Application filed August 1, 1928. Serial No. 296,783.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

The subject of this invention is a fuse for projectiles.

In separate loading ammunition the muzzle velocity and the consequent speed of rotation of the projectile varies in accordance with the powder charge. A consideration of this variation in the speed of rotation of the projectile has led to the design of the present fuse in which is incorporated a novel arming device whose movement to released position is initiated on set-back and completed on rotation of the projectile.

With the foregoing and other objects in view, my invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawings, wherein:

Fig. 1 is a longitudinal sectional view of the improved fuse shown in the unarmed position;

Fig. 2 is a similar view showing the parts in the armed position;

Figs. 3 to 6 are sectional views taken on their respective lines of Fig. 1;

Fig. 7 is a view in elevation of the explosive train assembly before insertion in the fuse casing.

Referring to the drawings by numerals of reference:

The invention is illustrated in connection with a combination fuse which may be set to provide instantaneous or delay functioning on impact. The fuse container consists of a tubular body 5 to which is attached a head 6. Within the body is a carrier 7 having an axial explosive train, including a primer 8, a delay element 9 and a detonator 10, and also formed with non-axial flash passages 11 converging to the detonator. Mounted forward-

ly of the carrier and held thereto by a sleeve 12 is a flash tube 13 whose flash passages are in communication with the primer 8 and with the non-axial passages 11. Interposed between the carrier and flash tube is a shutter 14 which may be moved to close the non-axial path of ignition transmission 11 leading directly to the detonator. The axial path leading to the primer 8 and delay element 9 is always open.

Movement of the shutter is accomplished through the sleeve 12 which is formed at its lower end with spaced prongs 15 between which are disposed peripheral lugs 16 of the shutter. The prongs of the sleeve are bent inwardly to engage in an annular recess 17 in the carrier. Stamped from the upper portion of the sleeve are fingers 18 bent inwardly to restrain the flash tube against longitudinal displacement and also to engage in peripheral recesses 19 in the flange of a rotatably mounted plunger 20 so that rotation of the plunger will be transmitted to the shutter.

The plunger is in the form of a tube which is mounted on the flash tube and carries intermediate its ends a primer detonator 21 which is to be fired by a striker 22 mounted in the head 6 of the fuse. Secured to the forward portion of the plunger is a squared cap 23 inserted through a correspondingly shaped aperture in a setting disk 24 marginally seated on an annular shoulder 25 at the forward end of the fuse body. The disk is formed with peripheral recesses 26 in which are inserted fingers 27 stamped from the flange 28 of a setting sleeve 29 so that upon rotation of the sleeve the disk and plunger will partake of this movement. The flange 28 of the sleeve rests on the marginal portion of the disk and both members are secured against longitudinal displacement when the fuse head 6 is attached to the fuse body.

Embracing the plunger in rear of the squared cap 23 is a cage 30 confining an arming spring 31 which is seated on a ring 32 on the forward end of the sleeve 12 and also confining a creep spring 33 which is seated on the base of the plunger. The springs 31 and 33 are separated by a sleeve 34 having

forwardly extending projections 35 which serve for securing blades 36 to the cage. The blades are preferably four in number, spaced equidistantly, and reinforced by a longitudinal rib 37. Their free extremities each terminate in a latch head 38 engageable in notches or cavities 39 in a retaining ring 40 (see Figs. 4 and 7) fixed to the carrier. When the blades are thus engaged the cage 10 will be held against the action of the arming spring 31 and the plunger will correspondingly be held in the unarmed position as shown in Fig. 1.

Disengagement of the blades is initiated 15 when the force of set-back occasioned by firing a projectile causes the cage and blades to travel to the rear and when this force has abated the centrifugal force due to rotation of the projectile will throw the blades outwardly until the latch heads contact the inner wall of the fuse body in which position they will be clear of the retaining ring 40. The arming spring 31 then acts to move the cage 20 forwardly until it is brought up against the setting disk. The cage by engaging the squared cap 23 of the plunger carries the plunger to the armed position as shown in Fig. 2 where the primer detonator is within the stroke of the firing pin on impact.

30 The blades are also utilized to releasably hold a spring actuated ring 41 which embraces the carrier 7 and is formed with a depending finger 42 positioned in the path of a movable detonator carrier which in the 35 present instance is shown as a centrifugally operable slide 43 carrying a detonator 44. The slide and its casing 45 are retained in place by a booster casing 46. When the cage is moved to the armed position the ring 41 will be moved by its spring 47 to withdraw 40 the finger 42 and permit the slide to arm. Movement of the ring 41 is arrested by the retaining ring 40.

I claim:

45 1. In a fuse, an explosive train carrier, a plunger mounted on the carrier, a cage embracing the plunger and engageable therewith, a creep spring confined between the cage and plunger, an arming spring confined 50 between the cage and the carrier, a sleeve separating the springs and secured to the cage, spaced blades secured to the cage and terminating in latch heads, a retaining ring fixed on the carrier and formed with recesses for 55 receiving the latch heads, a ring embracing the carrier, a spring holding the ring in contact with the ends of the latch heads, a depending finger on the ring and a movable detonator carrier held in unarmed position by 60 the finger.

2. In a fuse, an explosive train carrier, a plunger mounted on the carrier, a cage embracing the plunger and engageable therewith, a creep spring confined between the 65 cage and plunger, an arming spring con-

fined between the cage and the carrier, a sleeve separating the springs and secured to the cage, spaced blades secured to the cage and terminating in latch heads, and a retaining ring fixed on the carrier and formed with recesses for receiving the latch heads. 70

3. In a fuse, an explosive train carrier, a plunger mounted on the carrier, a cage embracing the plunger and engageable therewith, an arming spring confined between the 75 cage and the carrier, spaced blades secured to the cage and terminating in latch heads, and a retaining ring fixed on the carrier and formed with recesses for receiving the latch heads. 80

4. In a fuse, a cage, a spring for moving the cage, a plunger mounted for movement by the cage and also for independent movement, spaced blades secured to the cage and terminating in latch heads, and a fixed retaining ring formed with recesses for receiving the latch heads. 85

5. In a fuse, a member mounted for longitudinal movement, means releasable on set-back thereof by centrifugal force for latching said member against movement, a transversely movable member and spring actuated means retained by the latching means for opposing movement of the transverse member. 90

6. In a fuse, a member mounted for longitudinal movement, a member mounted for transverse movement and longitudinally disposed means releasable on set-back thereof by centrifugal force for holding said members 100 against movement.

7. In a fuse, a member mounted for longitudinal movement thereof, a member mounted for transverse movement thereof and means for holding said members having first a longitudinal and then a radial movement in 105 releasing. 110
